Dec. 338

Samuel Pierce of Troy N. Y. Assignor to
Johnson, Cox, and Fuller
Letters Patent No. 338. Dated Dec^o 3° 1850.

The Schedule referred to in these Letters Patent and making part of the same.

To all to whom these presents shall come:

Be it known that I, Samuel Pierce, of Troy, in the County of Rensselaer and State of New York, have invented, or produced a new and original design of Cook Stove, which I call the "Union of the States" and I do hereby declare that the following is a full and exact description of the same, reference being had to the annexed drawings making a part of this Specification, in which Fig. 1. is a front view, and Fig. 2. a side view of the stove.

The ornamental design of my stove consists in ornaments a. a., representing rosettes in the centre of the doors, and rays b. b., issuing therefrom, surrounded by mouldings on the outward edges of the plate and arabesque ornaments c. & d. surrounding the stove near the bottom as represented.

What I claim as new and desire to secure by Letters Patent, is the design of ornaments & configuration of Cook Stove, substantially the same as herein described and represented.
